US0D1012087S

(12) **United States Design Patent** (10) Patent No.: **US D1,012,087 S**
(45) Date of Patent: ** *Jan. 23, 2024

(54) **COMPUTER HUB**

(71) Applicant: **SARIANA, LLC**, San Diego, CA (US)

(72) Inventors: **Alan Turksu**, San Diego, CA (US);
Mustafa Burak Guclu, San Diego, CA (US)

(73) Assignee: **SARIANA LLC**, San Diego, CA (US)

(*) Notice: This patent is subject to a terminal disclaimer.

(**) Term: **15 Years**

(21) Appl. No.: **29/798,971**

(22) Filed: **Jul. 12, 2021**

(57) **CLAIM**

The ornamental design for a computer hub, as shown and described.

DESCRIPTION

FIG. 1 is a top, front, and left perspective view of a computer hub showing our new design;

FIG. 2 is a bottom, rear, and right perspective view thereof;

FIG. 3 is a left elevational view thereof;

FIG. 4 is a right elevational view thereof;

FIG. 5 is a top plan view thereof;

FIG. 6 is a bottom plan view thereof;

FIG. 7 is a front elevational view thereof;

FIG. 8 is a rear elevational view thereof; and,

FIG. 9 is a top, front, and left perspective view of the computer hub shown in an exemplary embodiment of use. The broken lines in the figures represent portions of the computer hub and a computer that form no part of the claimed design.

1 Claim, 9 Drawing Sheets
